UNITED STATES PATENT OFFICE.

FRANK O. HELLSTROM, OF BISMARCK, NORTH DAKOTA.

SILO.

1,289,457.

Specification of Letters Patent. Patented Dec. 31, 1918.

Application filed July 13, 1915. Serial No. 39,653.

To all whom it may concern:

Be it known that I, FRANK O. HELLSTROM, a citizen of the United States, residing at Bismarck, in the county of Burleigh and 5 State of North Dakota, have invented a new and useful Silo, of which the following is a specification.

The device forming the subject matter of this application is a frost proof and heat 10 proof structure embodied in the present instance in the form of a silo, and one object of the present invention is to provide a device of this type embodying blocks of a novel form, which blocks coöperate to define dead 15 air passages in the walls of the silo.

Another object of the invention is to improve the door construction of the silo.

A further object of the invention is to provide novel means for binding together 20 the constituent parts of the wall, and to provide a series of elements which, at once, serve to space apart the constituent members of the wall and to support the reinforcing element whereby the aforesaid binding is 25 effected.

A further object of the invention is to provide a structure of the class described in which the members which bind together the constituent parts of the wall may be used 30 either to define vertically separated, circumferentially continuous, dead air spaces, or to define vertically communicating air spaces extending from the top of the silo to the bottom thereof.

35 With the above and other objects in view which will appear as the description proceeds, the invention resides in the combination and arrangement of parts and in the details of construction hereinafter described 40 and claimed, it being understood that changes in the precise embodiment of the invention herein disclosed can be made within the scope of what is claimed, without departing from the spirit of the invention.

45 In the accompanying drawings:—

Figure 1 shows in front elevation, a silo embodying the present invention;

Fig. 2 is a cross section of a silo embodying the invention;

50 Fig. 3 is a fragmental perspective showing a portion of the wall;

Figs. 4 and 5 are detailed perspectives illustrating the various forms of blocks which enter into the construction of the 55 wall;

Fig. 6 is a diagrammatic plan of the rein-

forcement which binds together the constituent parts of the wall;

Fig. 7 is a fragmental perspective showing a modified form of the invention; 60

Fig. 8 is a top plan showing a modified form of reinforcement;

Fig. 9 is a fragmental perspective illustrating a modified form of the invention.

The structure forming the subject matter 65 of this application preferably comprises inner blocks 1 and outer blocks 2. The blocks 1 and 2 may be fashioned from concrete or any other suitable material. The inner blocks 1 may have outwardly projecting lugs 3 at their upper corners, and the outer blocks 2 may have inwardly projecting lugs 4 at their upper corners. The blocks 1 and 2 are erected in horizontal 70 courses on a suitable foundation 5, the lugs 3 of the inner blocks 1 abutting against each other in adjoining blocks as shown at 6, and the lugs 4 of the outer blocks 2 abutting against each other in adjoining blocks as 75 shown at 7. As indicated at 8, the lugs 3 of adjoining inner blocks 1 abut against the outer blocks 2, between the lugs 4, the inwardly projecting lugs 4 of the blocks 2 abutting against the blocks 1 between the lugs 3 on the blocks 1. Owing to the construction 80 above outlined, the wall of the silo embodies a plurality of dead air spaces 10 and the construction is such that the blocks 1 and 2 may be shifted circumferentially with respect to each other, whereby the vertical or 85 upright edges 12 of the blocks 1 may be disposed in break joint order with respect to the vertical or upright edges 14 of the outer blocks 2.

90 Interposed between the respective courses 95 of blocks 1 and 2 is a foraminous reinforcement 11 which may be a section of expanded metal, wire netting or the like, the reinforcement serving to bind the parts of the wall together, without interfering with the 100 communication between the various parts of the dead air chambers.

Certain of the wall forming blocks are beveled to form projecting angles 15 defining the edges of a door opening, such edges 105 receiving a frame 16 of V-shaped cross section, the frame 16 embodying protruding angles 17. The door preferably is made up of a pair of sections 18 constructed substantially like the blocks 1 and 2, these sections 110 being beveled as indicated at 19 to define reentrant angles receiving the protruding

angles 17 of the frame 16. The door forming sections 18 are united by means of a clamping device which may be in the form of a bolt 20, the head of the bolt being countersunk into the rearmost door section and the forward end of the bolt being provided with a lever nut 22 which bears against the outermost door section. In Fig. 2 of the drawings, the recess in which the bolt head is mounted, is shown at 21.

It will be understood readily that by tightening up the bolt and nut structure 20—22, the door sections 18 will be held securely in place.

15 The door sections may carry steps 23 and if desired, steps 25 may be mounted between certain of the courses in the wall of the silo.

An upright frame 24 may be attached to the wall of the silo adjacent the doors, the frame, denoted by the numeral 24, being adapted to receive landings coacting with the respective doors. In Fig. 1 of the drawings, the frame has been omitted, for the sake of clearness in disclosing the silo proper, the frame above mentioned being common and well known.

As shown in Fig. 7, the silo is made up of hollow tiles 100, the reinforcement appearing as shown at 101.

30 As delineated in Fig. 8, the reinforcement may be in the form of a thin, crossed metallic strip 102.

The reinforcing member, whatever be its form, not only binds the inner and outer parts of the wall together, but also strengthens the structure so that it will stand lateral strains, the bursting of the silo wall

from outward pressure due to an outward pressure of the contents of the silo, being to a remote possibility.

40 As shown in Fig. 9 of the drawings, the constituent blocks of the inner and outer walls are denoted by the reference numeral 500 and are devoid of the lugs 4 and 3. The reinforcing member may be a continuous 45 sheet 500, devoid of openings. In this form of the invention, the air spaces defined by the reinforcing sheets 501 and the blocks 500 are separated from each other vertically. Those skilled in the art will understand that 50 more than two walls may be employed, the structure above alluded to involving a mere duplication of what is disclosed in the drawings and meriting neither extended explanation nor specific delineation.

55 Having thus described the invention, what is claimed is:—

In a building, a wall made up of superposed courses of inner and outer blocks, the inner blocks being provided with outwardly 60 projecting corner spacing lugs which engage the outer blocks, the outer blocks being provided with inwardly projecting corner spacing lugs which engage the inner blocks, 65 whereby the blocks are held spaced with a minimum surface contact to provide air spaces between the inner and outer blocks.

In testimony that I claim the foregoing as my own, I have hereto affixed my signature in the presence of two witnesses.

FRANK O. HELLSTROM.

Witnesses:

L. A. FLOREN,
F. E. McCURDY.
